ATTORNEYS

UNITED STATES PATENT OFFICE.

JOHN L. CUNNINGHAM AND MAURICE D. WHALEN, OF CRESO, IOWA; SAID WHALEN
ASSIGNOR TO SAID CUNNINGHAM.

VALVE-CAGE PULLER.

Application filed October 8, 1921. Serial No. 506,311.

To all whom it may concern:

Be it known that we, JOHN L. CUNNINGHAM and MAURICE D. WHALEN, citizens of the United States, and residents of Cresco, 5 in the county of Howard and State of Iowa, have invented certain new and useful Improvements in Valve-Cage Pullers, of which the following is a specification.

This invention relates to a valve cage 10 puller.

The object of the invention is to provide a device of the above character by which the valve cage of the type employed for overhead valves in internal combustion engines 15 may be lifted or pulled in an expeditious manner and without injury.

It is also an object of the invention that the device be simple in construction and inexpensive to manufacture.

Other objects and objects relating to details of construction, combination and arrangement of parts will hereinafter appear in the detailed description to follow.

The invention is illustrated by way of 25 example in the accompanying drawings, in which—

Figure 1 is a sectional perspective view illustrating the application of the invention.

Figure 2 is a detail sectional view illustrating the structure of the puller stand or support, and

Figure 3 is a transverse sectional view of the same.

Referring to the drawings more particularly, 10 indicates generally a portion of a cylinder which is formed with the usual ledge 11. The cylinder is equipped with overhead valves one of which is shown in

40 detail. The valve shown comprises a cage 12 adapted to seat the valve member 13. The valve member 13 has the usual stem 14 which passes through the sleeve 15. Also there is shown the usual coil spring 16, washer 17 and lock nut 18.

In carrying out the invention there is provided the tubular member 19 which is formed with a slot 20 extending longitudinally thereof from a point intermediate its ends 50 to a point adjacent its upper end; and each edge of the slot is formed with a series of notches 21. A rod 22 is slidably fitted in the upper end thereof, said rod carrying a pin 23 adjacent its lower end adapted to be brought into engagement with either of the

notches 21 for adjusting the rod 22 with respect to the tube 19. The upper end of the rod 22 is formed with a bifurcated head as at 24 and between the bifurcations there is pivoted or fulcrumed a lever bar 25 by 60 the means of a pin 26. Also the bar is provided with the openings 26' by which the point of fulcrum may be adjusted.

The lever bar 25 is fulcrumed adjacent its forward end and its rear end portion is 65 shaped to serve as a handle as at 27 while its forward end terminates in a hook 28. To the hook 28 there is connected a swivel 29 which pivotally supports the two links 30. To the lower end of each link 30 there is pivotally 70 connected a handle 31 of the pincers 32, the jaws 33 of the pincers being adapted for engaging the valve stem 14.

In the operation of the present device the same is positioned as in Figure 1, and the 75 rod or stem 22 adjusted so the lever bar 25 will have the proper height. Previous to this, however, the lock nut 18 should be removed so that the cage 12 is free to be lifted. By downward pressure upon the handle 80 portion 27 of the lever bar 25, the cage may be raised in an easy and expeditious manner.

We claim:

1. In a device of the character described, 85 a tubular supporting member having a longitudinally extending slot in its upper end portion with a plurality of notches formed in each of the edges forming said slot, a stem slidably extending into the upper end of the tubular support, and a pin carried by said stem and extending laterally therefrom adapted to be brought to engage in said notches whereby said stem may be adjustably raised and lowered.

2. In a lifting device of the character described, a supporting tubular member having a longitudinally extending slot in an upper end portion thereof, said slot having notches formed upon its edges which occur in alternate relation, a stem slidable into the 90 upper end portion of said tubular member, a pin extending laterally from said stem and adapted to be engaged in any of said notches whereby to adjustably raise and lower said stem.

3. In a lifting device of the character described, a tubular supporting member having an upper end portion thereof formed with a longitudinally extending slot, said slot being closed at each of its ends and hav- 110

ing formed upon each of its edges a plurality of notches, a stem slideable within the upper end portion of said tubular member, and a pin extending laterally from said stem and adapted to be brought to engage in any of said notches whereby the stem may be adjustably raised and lowered.

4. In a lifting device of the character described, a tubular support having its one end portion formed with a slot, said slot being closed at each of its ends and having each of its edges formed with a plurality of

notches, a stem slideable within the upper end portion of said tubular support, a pin extending laterally from said stem, said pin being equal in length to the thickness of said tubular member and terminating at its outer end in a head adapted to resist movement through said slot and said pin being also adapted to be brought to engage in any of said notches whereby the stem may be adjustably raised and lowered.

JOHN L. CUNNINGHAM.
MAURICE D. WHALEN.
